UNITED STATES PATENT OFFICE.

EDWIN L. BUSHNELL, OF POUGHKEEPSIE, NEW YORK.

IMPROVED SPRING-MATTRESS.

Specification forming part of Letters Patent No. **95,984**, dated October 19, 1869.

To all whom it may concern:

Be it known that I, EDWIN L. BUSHNELL, of Poughkeepsie, in the county of Dutchess and State of New York, have invented certain new and useful Improvements in Spring-Mattresses; and I do hereby declare that the following is a full, clear, and exact description thereof, reference being had to the accompanying drawings, making part of this specification, and to the letters of reference marked thereon, like letters indicating like parts wherever they occur.

To enable others skilled in the art to construct and use my invention, I will proceed to describe it.

My invention relates to a spring-mattress; and it consists in a series of coiled or helical springs provided with eyes, and connected together by cords in such a manner as to hold them in their proper relative positions, the whole forming a light and elastic mattress, answering all the purposes of the ordinary bed-bottom, with the advantage that it can be rolled up into a compact form for storage or transportation.

In the drawings, Figure 1 is a horizontal section through my mattress, taken on the line $\alpha\alpha$ of Fig. 2; and Fig. 2 is an end view of the mattress.

A are the springs, made in any of the common forms, and provided at each end with four small eyes, a , made by twisting the wire at those points, as shown in Fig. 1. These springs I arrange close together in rows, so as to form the outline of the required mattress, and so that the eyes of each spring shall be in contact with the eyes of adjoining springs.

Across the top and bottom of each row of springs I place cords e , and at right angles to the cords e , but also on top and bottom of springs, place cords f . By means of these cords I fasten all the adjoining eyes of adjacent springs securely together, and I also knot the cords together where they cross each other at the centers of the springs, as shown in Fig.

1. The top and bottom eyes on the outer side of the outside springs I connect by cords e , as shown in Fig. 2. When the springs are thus arranged they form a light, strong, and elastic spring-mattress, which can be used in any ordinary bedstead without changing or altering the same in any way.

This mattress does not lose its form by use, nor do the springs become bent out of shape, as frequently happens in bed-bottoms, as by my method of connecting springs weight cannot be applied to them singly. When strain or weight is applied to any one of the series of springs, the cords e f , communicating with the adjoining springs, distribute the strain over several of the series.

My principle of construction may be applied not only to mattresses, but to pillows, cushions, &c., the cords e being shortened in those cases to give the articles a rounded form on the edges.

When my mattress is to be stored or transported it can be rolled up, either crosswise or lengthwise, into a compact and convenient form, and it will, upon being released, immediately resume its original form.

This mattress is cheaper, lighter, and more elastic than those in which wooden slats are used, and, unlike them, affords no protection for vermin.

It is obvious that there are many ways of connecting the springs by cord besides that shown in the drawings, the manner shown being, however, considered the best.

Having thus described my invention, what I claim is—

1. The spring A, having the eyes a formed thereon at each end, as set forth.
2. A spring-mattress consisting of a series of springs, A, with eyes e , united by cords e and f , as described.

EDWIN L. BUSHNELL.
